WATER PUMP DEVICE

John F. Sutcliff, New York, N. Y.

Application December 9, 1938, Serial No. 244,747

6 Claims. (Cl. 103—55)

This invention relates to new and useful improvements in a water pump device.

The invention has for an object the construction of a water pump device which is characterized by a high elevation tank for storing water to be subsequently used for power or other purposes, a low elevation cylinder having a closed bottom with a vertically projecting tube, a hollow piston engaging into said cylinder, and a novel mechanism for operating the hollow piston to pump water up to the high elevation tank.

The invention contemplates the provision of a vertically projecting tube upon a closed bottom of the hollow piston, and it is proposed to slidably 15 and intimately engage this tube over the tube of said cylinder. Furthermore, it is proposed to provide a valve for closing the outer tube and a means for opening said valve in the down position of the piston for discharging the water from the piston.

Still further the invention proposes the provision of a tank with a filter and positioned below said valve, a pipe system for connecting the tank and the cylinder, and valves arranged in a manner to facilitate the pumping of water to the high elevation tank.

Still further the invention proposes the utilization of a natural force means for assisting in reciprocating the piston for pumping the water.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a vertical sectional view of a water pump device constructed according to this invention.

Fig. 2 is a fragmentary vertical sectional view on the line 2—2 of Fig. 1.

Fig. 3 is a fragmentary vertical sectional view taken on the line 3—3 of Fig. 1.

Fig. 4 is a detailed view of a portion of Fig. 3 but showing the parts in a different position.

The water pump device, according to this invention, includes a high elevation tank 10 for storing water to be subsequently used for power or other purposes. A low elevation cylinder 11 has a closed bottom 11^a with a vertically projecting tube 12. A hollow piston 13 engages within the top of the cylinder 11 and has a closed bottom 13^a with a vertically projecting tube 14

slidably and intimately engaging over the tube 12. A valve 15 closes the said outer tube 14.

A means is provided for opening the valve 15 in the down position of the piston. This means includes an arrangement whereby the valve 15 has a skirt portion 15^a engaging into the top of the tube 14. This skirt portion has several openings 16 which are normally covered by the tube 14 in the lowered position of the valve 15. The upper end 12^a of the tube 12 is adapted to 10 strike the skirt 15^a when the piston 13 is at the bottom of its stroke for lifting the valve as shown in Fig. 4. This latter position represents the open position of the valve.

A tank 17 is provided with a filter 18 and the 15 tank is arranged below the valve 15. A pipe 19 extends from the bottom of the inner tube 12 to the top of the tank 17, above the filter 18. Another pipe 20 extends from the bottom of the tank 17 below the filter 18, to the bottom of the 20 cylinder 11. This pipe 20 is provided with a one-way valve 21 arranged to permit the passage of water from the tank 17 into the cylinder 11. Another pipe 22 extends from the cylinder 11 upwards to the high elevation tank 10. This pipe 25 22 is provided with a one-way valve 23 for permitting the passage of water from the cylinder 11 to the tank 10.

A water supply is provided for supplying the piston 13 with water and includes a pipe 25 having a discharge end 25^a terminated above the piston 13. This pipe is supported by a bracket 26. The pipe 25 extends to a tank 27 which is below the surface of a stream 28 or some other supply of water. The pipe 25 is provided with a valve 29 which may be adjusted to control the volume of water that will discharge therefrom. The valve is to be open at all times to permit a continuous flow of water. A natural force means is provided for assisting in reciprocating the piston 13. This means includes a lever 30 which is pivotally mounted by a pintle 31 intermediate of its ends. The front end of the lever 30 is provided with a fork 30^a the arms of which are provided with slots 32 engaging a trunnion 33 mounted on the sides of the piston 13.

A heavy spring 34 normally urges the rear end of the lever 30 upwards against a cam 35. This cam is mounted upon a shaft 36 rotatively supported in bearings 37. The shaft 36 is provided with a bevel gear 38 meshing with a bevel gear 39 on a shaft 40 extending upwards. A water wheel 41 engages the stream 28 and is mounted on a shaft 42. The shafts 40 and 42 are connected with each other by bevel gears 43. 55

The cylinder 11 and mechanism associated with this cylinder are mounted in a large box 45 which is embedded in the ground 46 adjacent the stream 28. A manhole 47 is provided from the top of the ground through which access may be had to the mechanism within the box 45.

The operation of the device is as follows:

- Water flows from the tank 27 through the pipe 25 and discharges into the open top of the hollow piston 13. When this piston moves downwards and reaches substantially the bottom of the cylinder 11 the valve 15 will be opened because the skirt 15^a of the valve strikes the top portion 12^a of the inner tube 12. The water then flows through the open valve 15 down the inner tube 12 along the pipe 19 and discharges to the tank 17. From the tank 17 the water flows through the filter 18 through the pipe 20 and discharges at the bottom of the cylinder 11. When the piston 13 moves upwards the valve 21 opens and water is sucked in through the pipe 20. The valve 23 at this time closes to prevent water from being drawn out of the pipe 22. When the piston 13 reaches the top of its stroke and starts moving down the valve 21 will close and the valve 23 will open so that the water from the cylinder 11 is now forced through the pipe 22 up into the tank 10.
- 30 The reciprocation of the cylinder 13 is partly accomplished by the spring 34 acting to move the piston 13 downwards. The cam 35 which is operated by the water wheel 41 engages against one end of the lever 30 and acts to move the piston 13 upwards.

While I have illustrated and described the preferred embodiments of my invention, it is to be understood that I do not limit myself to the precise constructions herein disclosed and the right 40 is reserved to all changes and modifications coming within the scope of the invention as defined in the appended claims.

Having thus described my invention, what I claim as new, and desire to secure by United 45 States Letters Patent is:

1. A water pump device, comprising a high elevation tank for storing water to be subsequently used for power or other purposes, a low elevation cylinder having a closed bottom with a vertically projecting tube, a hollow piston engaging into said cylinder and having a closed bottom with a vertically projecting tube slidably and intimately engaged over said tube, a valve closing said outer tube, means for opening said valve in the down position of said piston, a tank with a filter below said valve, a pipe from the bottom of said inner tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston.
- 60 2. A water pump device, comprising a high elevation tank for storing water to be subsequently used for power or other purposes, a low elevation cylinder having a closed bottom with a vertically projecting tube, a hollow piston engaging into said cylinder and having a closed bottom with a vertically projecting tube slidably and intimately engaged over said tube, a valve closing said outer tube, means for opening said valve in the down position of said piston, a tank with a filter below said valve, a pipe from the bottom of said inner tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, comprising a water wheel connected with rotation transmission

tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, said water supply being controlled with a valve which may be adjusted to control the rate and volume of water discharging therefrom.

3. A water pump device, comprising a high elevation tank for storing water to be subsequently used for power or other purposes, a low elevation cylinder having a closed bottom with a vertically projecting tube, a hollow piston engaging into said cylinder and having a closed bottom with a vertically projecting tube slidably and intimately engaged over said tube, a valve closing said outer tube, means for opening said valve in the down position of said piston, a tank with a filter below said valve, a pipe from the bottom of said inner tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, said means for opening the valve comprising an abutment against which the valve strikes in the lowered position of the piston.

4. A water pump device, comprising a high elevation tank for storing water to be subsequently used for power or other purposes, a low elevation cylinder having a closed bottom with a vertically projecting tube, a hollow piston engaging into said cylinder and having a closed bottom with a vertically projecting tube slidably and intimately engaged over said tube, a valve closing said outer tube, means for opening said valve in the down position of said piston, a tank with a filter below said valve, a pipe from the bottom of said inner tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, said means for opening the valve comprising an abutment against which the valve strikes in the lowered position of the piston.

5. A water pump device, comprising a high elevation tank for storing water to be subsequently used for power or other purposes, a low elevation cylinder having a closed bottom with a vertically projecting tube, a hollow piston engaging into said cylinder and having a closed bottom with a vertically projecting tube slidably and intimately engaged over said tube, a valve closing said outer tube, means for opening said valve in the down position of said piston, a tank with a filter below said valve, a pipe from the bottom of said inner tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, comprising a water wheel connected with rotation transmission

mechanism, a cam operated by said rotation transmission mechanism, a lever pivotally mounted and connected with said cylinder, and said cam oscillating said lever.

- 5 6. A water pump device, comprising a high elevation tank for storing water to be subsequently used for power or other purposes, a low elevation cylinder having a closed bottom with a vertically projecting tube, a hollow piston engaging into
10 said cylinder and having a closed bottom with a vertically projecting tube slidably and intimately engaged over said tube, a valve closing said outer tube, means for opening said valve in the down position of said piston, a tank with a filter below
15 said valve, a pipe from the bottom of said inner

tube to said tank with the filter, a pipe from said tank with the filter to the bottom of said cylinder and having a one way valve permitting the passage of water to said cylinder, a pipe from said cylinder to said high elevational tank and having a one way valve, a water supply to said piston, and natural force means for assisting in reciprocating said piston, comprising a water wheel connected with rotation transmission mechanism, a cam operated by said rotation transmission mechanism, a lever pivotally mounted and connected with said cylinder, and said cam oscillating said lever, and a heavy spring urging the lever to maintain its connection with the cam.
